UNITED STATES PATENT OFFICE.

GEORGE H. FORSYTH, OF CHICAGO, ILLINOIS, ASSIGNOR, BY MESNE ASSIGNMENTS, TO
WAUGH DRAFT GEAR COMPANY, A CORPORATION OF ILLINOIS.

DRAFT-RIGGING.

1,192,513.

Specification of Letters Patent. Patented July 25, 1916.

Application filed February 21, 1912. Serial No. 679,035.

To all whom it may concern:

Be it known that I, GEORGE H. FORSYTH, a citizen of the United States, residing at Chicago, in the county of Cook and State 5 of Illinois, have invented certain new and useful Improvements in Draft-Rigging, of which the following is a specification.

My invention relates to draft rigging for railway cars, and pertains generally to that 10 class of draft rigging devices which is employed in association with a longitudinally movable member, adapted to transmit draft and buffing strains, elastic resistance devices to absorb such strains, and follower members 15 through which the strains are imparted to said resistance devices and to the draft sills of the car.

Certain features of the invention further relate to novel arrangements of stops and 20 motion transmitting members for the followers.

The principal object of the present invention is to provide a draft rigging of high capacity which will at the same time permit 25 relatively long travel or longitudinal movement of the draw-bar, together with means whereby the draft and buffing strains are distributed to effect the prevention of breakage or unusual wear of parts.

Preferred means for accomplishing the above-mentioned and other objects are illustrated in the accompanying drawings forming 30 a part of this specification, and in which:

Figure 1 is a top plan view of the device, and Fig. 2 is a side elevation thereof. In 35 each view the parts are shown in section.

In the construction herein illustrated and described the center sills 5, comprising outwardly-turned channel irons, are arranged 40 in the usual manner. On the inside surface of the sills three pairs of oppositely disposed stops, 6, 6, 7, 7 and 8, 8, are secured by riveting. To reduce the shearing strain 45 upon the rivets and to provide stronger connection between the stops and the center sills, these stop castings are preferably provided with lugs 6', 7' and 8', which are accommodated in suitable apertures 6^a, 7^a and 50 8^a, respectively, in the sills 5. The draft bar 9 is provided with the usual yoke or extension 10.

As will be readily observed from the drawings, the end and intermediate stops

6, 7 and 8 divide the space between the center 55 sills into two compartments or pockets 11 and 12. These pockets accommodate the two pairs of reversely disposed follower blocks 13 and 14, 15 and 16, each of which followers is provided with a convexly curved 60 bearing surface 13', 14', 15' and 16', respectively, substantially as shown. Between the end follower 13 and the intermediate follower 14 is what I shall term a medial follower 17, and between the intermediate follower 15 and the end follower 16 is a similar medial follower 18, which medial followers 17 and 18 are, respectively, provided with double concave gearing surfaces 17' and 18' of substantially the same curvature as that 70 of the convex bearing surfaces on the intermediate and end followers mentioned. Groups of spring plates 19, 20, 21 and 22 between the end and medial and between the medial and intermediate followers 75 respectively, and coöperating therewith, constitute the elastic resistance media of the device. A sliding block 23, conveniently held in position and guided by the inner surfaces of the intermediate stops 7, has its 80 ends in contact with the intermediate followers 14 and 15 respectively, while the inner surfaces of the draw-bar 9 and the yoke 10 contact respectively the end followers 13 and 16. The followers and spring elements 85 are suitably held in alined position horizontally by supporting plates 24 bolted to the stop castings.

The illustration of Fig. 1 shows this draw-bar mechanism in normal position—that is, 90 ready to receive either draft or buffing strains. In this position the followers 13 and 16 are in contact with the stops 6 and 8 respectively, there being normally a space between each of the followers 14 and 15 and 95 the intermediate stops 7 to allow movement of the draw-bar in either direction and to communicate motion from one group of spring elements to the other. It will now be understood that when a buffing strain comes 100 upon the draw-bar, such strain will be communicated through all of the springs and followers and the sliding block 23, to the stop 8, and that each of the spring plates in each of the groups of spring elements will 105 be flexed through the arrangement of alternate convex and concave spring-pressing surfaces on the followers. It is also apparent

that as the pressure or strain continues, the follower 14 is naturally forced into contact with the stops 7.

The movement of the draw-bar 9 under 5 buffing strain when the follower 14 is in contact with the stops 7 (assuming the strength of the spring elements in each pocket to be the same) is double the movement which would have taken place if the draw-bar had 10 acted upon the spring elements of only one of the pockets, and, in any event, the total movement of the draw-bar is equal to the sum of or combined movement of all of the groups of spring elements in the device.

15 It is evident that if the several groups of spring elements have substantially the same power of resistance, said spring elements will reach their maximum efficiency, or, in other words, go solid, at substantially the same time and after substantially the same degree of flexure or travel. The arrangement of the intermediate stops 7 is such that the follower 14 comes into abutment therewith at substantially the same instant that 20 the spring elements in each of the two pockets go solid. Under draft strains the action is the same, but in reversed order, the follower 15 contacting the intermediate stops 7 at the instant the groups of spring elements 25 become rigid, as will be readily understood.

30 As the spring plates mentioned may be readily inserted in or withdrawn from any of the several groups thereof, it is evident that the resistance of these spring elements 35 may be made as desired. It is also clear that the strength of the springs in one pocket may be made greater than in another, whereby after the springs in one pocket have gone solid there will still be a residual resiliency 40 in the spring elements of the other pocket. By this arrangement the ordinary buffing strains may be absorbed by the combined action of the springs of the two pockets acting through the desired long travel afforded by 45 the present arrangement, while additional buffing shocks will be at least partially absorbed by the residual resiliency of the other spring elements before the spring elements 50 are all solid and the end and intermediate stops receive any final strains too great for the springs to carry.

55 While there are shown in the drawings clusters of the same number of spring plates of substantially the same capacity, the plates in one pocket may, of course, be made heavier, and, consequently, a smaller number thereof used than in the other pocket. And while there has been shown a pair of intermediate followers communicating strains from one 60 to the other through a movable block, it is pointed out that these two followers and the block may be formed integral with each other or otherwise rigidly connected.

65 It will be apparent that many other changes may be made in the construction

and arrangement of the various parts herein illustrated and described without departing from the spirit or scope of this invention.

What I claim is:

1. In a draft rigging, the combination of a draw-bar, a yoke thereon, an end follower abutting said draw-bar, an end follower abutting said yoke, a longitudinally movable block, a follower abutting each end 70 respectively of said movable block, an abutment stop between said last-mentioned followers, one of which followers is adapted to contact said abutment stop under draft strains and the other is adapted to contact 75 the same under buffing strains, and spring elements disposed between said end followers and said second-mentioned followers respectively, the arrangement being such that the total movement of the draw-bar under 80 draft or buffing strains is equal to the combined movement of said spring elements, substantially as described.

2. In a draft rigging, the combination of a draw-bar, an extension thereon, end followers in abutment with said draw-bar and extension respectively, end abutment stops normally in engagement with said end followers respectively, a pair of intermediate followers, an intermediate abutment stop 90 between and normally out of engagement with said intermediate followers, but adapted to be engaged by one of said intermediate followers under buffing strains and by the other under draft strains, rigid 95 strain-transmitting means between the intermediate followers, and spring elements between said intermediate and end followers respectively, the arrangement being such that the total movement of the draw-bar 100 equals the combined movement of said spring elements, and said abutment stop takes part of the buffing and draft strains, substantially as described.

3. In a draft rigging, the combination of 110 a draw-bar, an extension thereon, a plurality of sets of spring elements actuated by said draw-bar and extension, a rigid spacing element disposed between the sets of spring elements, end stops normally in engagement with said spring elements, an intermediate stop normally out of engagement with said spring elements but adapted to be engaged by one of said spring elements under buffing strains and by the other under 115 draft strains, whereby said intermediate stop receives part of the buffing and draft strains applied to said draw-bars, substantially as described.

4. In a draft rigging, the combination of 125 a draw-bar, an extension thereon, end and intermediate stops, end followers normally in engagement with said end stops, an intermediate follower member comprising a pair of rigidly spaced elements disposed on 130

opposite sides of and normally out of engagement with said intermediate stops, and spring elements between said end and intermediate followers respectively, there being no fixed connection between either said draw-bar or said extension and any of said followers or spring elements, substantially as described.

5. In a draft rigging, the combination of 10 a draw-bar, a connection therefor, end and intermediate stops, end and intermediate followers, spring elements between said end and intermediate followers respectively, the intermediate follower comprising a pair of 15 elements disposed on opposite sides of the intermediate stop, and a spacing block, movable with said intermediate follower relative to said draw-bar and stop, between said pair of elements.

20 6. In a draft rigging, the combination of a draw-bar, a yoke, end followers abutting respectively the draw-bar and yoke, an intermediate member comprising end follower elements and an intermediate connecting 25 block element moving therewith, end stops arranged to engage the end followers, and an intermediate stop disposed between the follower elements of the interposed member and adapted to contact with one of the fol- 30 lower elements under draft and with the other under buffing strains, and springs dis-

posed between said end followers and the follower elements of the intermediate member.

7. In a draft rigging, the combination of 35 a draw-bar, a connection therefor, an end follower abutting said draw-bar and an end follower abutting said connection, a spacing block longitudinally movable relative to said draw-bar and connection, a follower abut- 40 ting each end respectively, of said block, each of said followers having a curved spring-pressing surface, a plurality of groups of plate spring elements abutting the curved surfaces of said followers, other 45 followers between said groups of spring elements having opposite surfaces curved re- versely to the curvature of the follower sur- faces opposite them respectively, end and in- 50 termediate abutment stops adapted to en- gage the end and intermediate followers re- spectively, the arrangement being such that the total travel of the draw-bar is equal to the combined travel of the spring elements, and said intermediate stops absorb a por- 55 tion of the draft and buffing strains, sub- stantially as described.

GEORGE H. FORSYTH.
